The ornamental design for a controller for electrode patch, as shown and described.

DESCRIPTION

FIG. 1 is a perspective view of a controller for electrode patch; FIG. 2 is a front view of the controller for electrode patch shown in FIG. 1;

FIG. 3 is a left side view of the controller for electrode patch shown in FIG. 1;

FIG. 4 is a right side view of the controller for electrode patch shown in FIG. 1;

FIG. 5 is a top plan view of the controller for electrode patch shown in FIG. 1;

FIG. 6 is a bottom plan view of the controller for electrode patch shown in FIG. 1; and,

FIG. 7 is a rear view of the controller for electrode patch shown in FIG. 1.

The outermost broken lines showing rectangular shapes in FIGS. 3 and 4; and rectangular and circular shapes in FIG. 7 represent internal boundaries of the design. All broken lines themselves and the areas within them form no part of the claimed design.
